Primary Examiner — Richard Edgar*Assistant Examiner* — Alexander J David(74) *Attorney, Agent, or Firm* — Armstrong Teasdale LLP(57) **CLAIM**

The ornamental design for a bale mover as shown and described.

DESCRIPTION

FIG. 1 is a perspective view of a bale mover according to the new design.

FIG. 2 is a front view thereof.

FIG. 3 is a rear view thereof.

FIG. 4 is a left-side view thereof.

FIG. 5 is a right-side view thereof.

FIG. 6 is a top view thereof; and,

FIG. 7 is a bottom view thereof.

The broken lines in the drawings illustrate portions of the bale mover that form no part of the claimed design.

1 Claim, 6 Drawing Sheets(56)
